UNITED STATES PATENT OFFICE.

CLARENCE A. BODDIE, OF PITTSBURGH, PENNSYLVANIA, ASSIGNOR TO WESTINGHOUSE ELECTRIC & MANUFACTURING COMPANY, A CORPORATION OF PENNSYLVANIA.

FURNACE-REGULATOR SYSTEM.

Application filed June 25, 1919. Serial No. 306,726.

To all whom it may concern:

Be it known that I, CLARENCE A. BODDIE, a citizen of the United States, and a resident of Pittsburgh, in the county of Allegheny and State of Pennsylvania, have invented a new and useful Improvement in Furnace-Regulator Systems, of which the following is a specification.

My invention relates to regulator systems and particularly to systems for governing the operation of the movable electrodes in electric furnaces.

One object of my invention is to provide a furnace-regulator system that shall so operate the movable electrodes as to maintain a substantially-constant electrode arc and insure against "hunting action."

In an electric furnace of the movable-electrode type, it is necessary to keep adjusting each electrode, relative to the bath of material being treated, in order to maintain the power supplied to the furnace substantially constant. Such adjustment of the electrode by hand is impractical, inasmuch as it requires the constant attention of an operator and, moreover, it is difficult to obtain satisfactory or close regulation of a furnace by such method.

Heretofore, the regulation or adjustment of the movable electrode has been accomplished by means of a regulator which was operated in accordance with the current flowing through the furnace, or in accordance with the voltage obtained between the movable electrode and the bath of material being treated. However, such operation has proved defective in many cases by reason of the failure to provide reliable and effective means of preventing hunting action by the regulator.

In a furnace-regulator system constructed in accordance with my invention, the movable electrode is raised and lowered, relative to the bath of material being treated, by means of an electric motor which is governed, in accordance with the current flowing through the electrode, to maintain a substantially constant electric arc, and means is further provided for insuring against over-travel or so-called "hunting action" by the regulator.

In detail, the regulator, which governs the

operation of the electrode motor in a clockwise and in a counterclockwise direction for lowering and raising the electrode, comprises a main-control electromagnet and two switches which are operated by the main-control electromagnet. The main control electromagnet is energized in accordance with the current flowing through the associated electrode and is provided with an energizing winding, which is divided into two sections. The electromagnet selectively energizes said switches according to the amount of current flowing through the electrode, and the switches operate the electrode motor in a clockwise and in a counterclockwise direction in order to lower or raise the electrode. One of said switches is provided with an interlock switch member for connecting a resistor in shunt to one portion of said electromagnet winding in order to prevent "hunting action" when the motor is being rotated in a counterclockwise direction to reduce the current flow through the electrode. The second switch is provided with an interlock-switch member for connecting the second section of the electromagnet winding in shunt to a second resistor that is normally in series with the first winding section. The second interlock-switch member and the second resistor serve to prevent any "hunting action" by the regulator when the motor is being operated in a clockwise direction to lower the electrode and to increase the current flow through it. The two switches are further provided with interlock-switch members for establishing a brake circuit through the electrode motor upon release of them.

The single figure in the accompanying drawing is a diagrammatic view of a regulator system embodying my invention.

Referring to the drawing, an electric furnace 1, comprising a receptacle 2 containing a bath of material 3, and three movable electrodes 4, 5 and 6, is directly connected to a three-phase supply circuit comprising conductors 7, 8 and 9.

A motor is provided for raising and lowering each of the electrodes 4, 5 and 6, and a regulator is provided for each motor in order to control the motor in accordance with the current flowing through the associated electrode. Inasmuch as the motors as

sociated with the electrodes and the regulators for governing the operation of the motors are similar in construction and operation, it is deemed sufficient to illustrate and 5 describe only one regulator and the operation of one motor and one electrode by such regulator.

The electrode 6 is provided with a motor 10 for raising and lowering it, and a regulator 11 for governing the operation of the motor 10 in accordance with the current flowing through the electrode. The motor 10 comprises an armature 12 and a field winding 13 which is directly connected 15 across the supply circuit comprising conductors 14 and 15. The armature 12 of the motor 10 is mechanically connected to the electrode 6 in any suitable manner, as by means of a shaft 16, a winding drum 17, and 20 a flexible connector 18 which passes over a pulley 19.

The regulator 11 comprises a main control electromagnet 20, a switch 21, which is operated by the electromagnet 20 for effecting rotation of the motor 10 in a counterclockwise direction, and a switch 22 which is operated by the electromagnet 20 for effecting clockwise rotation of the motor 10. The electromagnet 20 comprises a winding 23 which is divided into two sections 23^a and 23^b, and a core armature 24 which is pivotally connected to a contact arm 25. The winding 23 is connected to the three-phase supply conductor 9 by means of a 30 current transformer 26 in order to operate the electromagnet in accordance with the current flowing through the electrode 6. The core armature 24 is provided with a dash-pot 27 for adjusting the speed of its 40 operation. A tap, which is joined to the winding 23 at the point of connection of the two sections 23^a and 23^b, is directly connected to two resistors 28 and 29, for completing circuits, in a manner to be herein-after set forth, to prevent "hunting action."

The contact arm 25 is pivotally mounted at 30 and is provided with two main contact members 31 and 32, which are mounted on the end of the contact arm 25 opposite 50 to the end connected to the core armature 24. The contact member 31 engages a main contact member 33, in one position of the contact arm, in order to increase the current flow through the electrode 6, and the 55 contact member 32 engages a contact member 34 in the opposite position of the contact arm, in order to complete a circuit for decreasing the current flow through the electrode 6. The contact members 31 and 32 60 are directly connected to the supply conductor 14.

The switch 21 comprises a winding 36, which is connected across the supply conductors 14 and 15 upon engagement of the contact members 32 and 34, and a core armature 70

37. The core armature 37 operates two switch members 38 and 39, and two interlock-switch members 40 and 41. The switch members 38 and 39 connect the armature 12 across the supply conductors 14 and 15 for effecting rotation of the motor 10 in a counterclockwise direction to raise the electrode 6 from the bath of material 3. The interlock-switch member 40 serves to connect the resistor 29 in shunt to the electromagnet winding section 23^a, for changing the setting of the regulator, upon operation of the switch 21, to prevent "hunting action" by the regulator when the electrode is being raised. 80

The switch 22 comprises a winding 42, which is connected across the supply conductors 14 and 15 upon engagement of the contact members 31 and 33, and a core armature 43 which operates two contact members 44 and 45 and two interlock-switch members, 46 and 47. The switch members 44 and 45 connect the armature 12 across the supply conductors 14 and 15 for rotating the motor 10 in a clockwise direction 90 in order to lower the electrode 6 in the furnace 1. The interlock switch member 46, upon operation of the switch 22, connects the winding section 23^b of the electromagnet 20 in circuit with the transformer 26 and in shunt to the resistor 28 which is normally in series with the electromagnet winding section 23^a. Such operation of the interlock member 46 serves to prevent "hunting action" by the regulator when the motor is 100 operated in a clockwise direction to lower the electrode 6. 95

The interlock-switch members 41 and 47 complete a circuit through a brake-relay 50 from the supply conductors 14 and 15 upon de-energization of the switches 21 and 22. The relay 50 completes a dynamic-braking circuit for the armature 12 through a resistor 51. When the motor 10 is operated, either in a counterclockwise direction or in a clockwise direction, the releasing of either the switch 22 or the switch 21 operates the brake magnet 50 for completing the dynamic-braking circuit to effect a quick stopping of the motor 10. 110

Assuming the apparatus of the system to be in the position shown in the drawing and a current below normal amount to flow through the electrode 6, then a decreased current flows through the winding section 23^a of the electromagnet 20 to operate the contact arm 25 and effect engagement between the contact members 31 and 33. In this regard, it should be noted that the circuit of the winding section 23^a is completed through the resistor 28, and the winding section 23^b and the resistor 29 are excluded from circuit. Upon engagement of the contact members 31 and 33, a circuit is completed, from the supply conductor 14, through 125 130

the contact arm 25, the contact members 31 and 33, and the winding 42, to the supply conductor 15. Thereupon, the switch 22 is operated for rotating the motor 10 in a clockwise direction to lower the electrode 6 and increase the current flow through it.

If the regulator 11 were controlled solely by the current flowing through the electrode 6 for stopping the operation of the motor 10, the main control magnet 20 would not be operated to disconnect the contact members 31 and 33 to release the switch 22 and stop the motor 10 until normal current conditions were obtained in the electrode circuit. Consequently, by reason of the inertia of the various moving parts of the regulator, it is seen that the motor 10 would overtravel to lower the electrode 6 beyond the determined point and, accordingly, to increase the current flow through the electrode above a normal amount. In order to prevent such overtravel and the resulting so-called "hunting action," the interlock switch member 46 is operated simultaneously with the energization 25 of the motor 10 to connect the winding section 23^a of the electromagnet 20 in shunt to the resistor 28. Thus, the setting of the regulator is changed and the contact arm 25 is operated to separate the contact members 31 and 33 just prior to the obtaining of normal current flow through the electrode 6.

In case the current flow through the electrode 6 is above normal amount, the electromagnet 20 operates the contact arm 25 to effect engagement between the contact members 32 and 34. Upon engagement of the contact members 32 and 34, a circuit is completed from the supply conductor 14 through the contact arm 25, the contact members 32 and 34, and the winding 36 to the supply conductor 15. Thereupon, the switch 21 is operated for effecting rotation of the motor 10 in a counterclockwise direction to raise the electrode 6 and decrease the current flow through it.

In order to prevent "hunting action" by the regulator when the motor is operating in a counterclockwise direction, the interlock-switch member 40 is operated simultaneously 50 with the energization of the motor 10 to connect the resistor 29 in shunt to the winding section 23^a of the electromagnet 20. Thus, the setting of the regulator is changed to effect separation of the contact members 32 and 34 just prior to the obtaining of normal current flow through the electrode 6.

From the above description, it is apparent that not only the number of effected turns of the winding 23 of the electromagnet 20 is varied, but also the resistance of the electromagnetic circuit is varied in order to prevent any "hunting action" when the electrode is being raised and lowered.

Modifications in the system and arrangement and location of parts may be made with-

in the spirit and scope of my invention, and such modifications are intended to be covered by the appended claims.

I claim as my invention:

1. In a furnace-regulator system, the combination comprising a movable electrode, means for raising and lowering the electrode, and a regulator for governing the operation of said means, said regulator comprising an electromagnet operated in accordance with the condition of the electrode circuit, and means for varying the number of effective turns in the magnet winding and for varying the resistance of the magnet circuit to prevent "hunting action." 70

2. In a furnace-regulator system, the combination with a movable electrode and means for raising and lowering the electrode, of a regulator for governing the operation of said means and comprising an electromagnet energized in accordance with the current flowing through the electrode, and means for varying the number of effective turns in the magnet winding and for varying the resistance of the magnet circuit to prevent "hunting action." 80

3. In a furnace-regulator system, a movable electrode, and means comprising a regulator for governing the operation of the electrode, said regulator comprising an electromagnet energized in accordance with the electrical condition of the electrode circuit and means for varying the number of effective turns in the magnet winding and for varying the resistance of the magnet circuit to prevent "hunting action." 95

4. In a furnace-regulator system, a movable electrode and means comprising a regulator for governing the operation of the electrode, said regulator comprising an electromagnet energized in accordance with the current flowing through the electrode and means comprising two resistors for varying the electromagnet circuit to prevent "hunting action" by the regulator. 105

5. In a furnace-regulator system, a movable electrode, a motor for raising and lowering the electrode, and a regulator for governing the operation of said motor, said regulator comprising an electromagnet and means for varying the resistance of the magnet circuit to prevent "hunting action" when the electrode is being raised and lowered. 115

6. In a furnace-regulator system, the combination with a movable electrode and means for raising and lowering the electrode, of a regulator for governing the operation of said means and comprising an electromagnet operated in accordance with the current flowing through the electrode, a resistor for shunting one portion of the magnet winding to prevent "hunting action" when the electrode is being raised, and a second resistor for shunting another 125

portion of the winding of said magnet to prevent "hunting action" when the electrode is being raised.

7. In a furnace-regulator system, the combination comprising a movable electrode, a motor for raising and lowering said electrode, and a regulator for governing the operation of said motor to maintain a constant electrode arc, said regulator comprising an electromagnet operated in accordance with the current flowing through the electrode and resistors for short-circuiting portions of the winding of the electromagnet to prevent "hunting action".

- 10 8. In a furnace-regulator system, a plurality of movable electrodes, and a regulator for governing the operation of each of said electrodes, each of said regulators comprising an electromagnet energized in accordance with the current flowing through the associated electrode and means for simultaneously varying the number of effective turns in the magnet winding and the resistance of the magnet circuit to prevent 25 "hunting action" by the regulator.

9. In a furnace-regulator system, the combination with a movable electrode, and a motor for raising and lowering said electrode, of a regulator for governing the operation of said motor to maintain a constant electrode arc, said regulator comprising an electromagnet having a winding divided into two sections and operated in accordance with the current flowing through the electrode, two resistors, a switch for connecting one resistor in shunt to one of said winding sections to prevent any "hunting action" during one operation of the electrode, and a second switch for connecting the second resistor in shunt to the second section of the magnet winding to prevent "hunting action" during another operation of the electrode.

10. In a furnace-regulator system, the combination with a movable electrode and a motor for raising and lowering said electrode, of a regulator for governing the operation of said motor to maintain a constant electrode arc, said regulator comprising an electromagnet having a winding divided into sections and energized in accordance with the current flowing through the electrode, two resistors, means for connecting one resistor in shunt to one section of said winding and the second resistor in series with said section to prevent "hunting action" when the electrode is being raised, and means for connecting the resistors severally in shunt to the two sections of said winding when the electrode is being lowered.

11. In a regulator system, a supply circuit, a resistance-varying means in said

circuit, a regulator comprising an electromagnet for operating said means to maintain substantially constant circuit conditions the 65 circuit of said electromagnet including external resistance and also means for varying the number of effective turns in the magnet winding and also for varying the resistance of the magnet circuit to prevent "hunting 70 action."

12. In a regulator system, the combination comprising a supply circuit, resistance-varying means in said circuit, a motor for operating said resistance-varying means and a regulator for governing the operation of said motor, said regulator comprising an electromagnet operated in accordance with the condition of the supply circuit, resistance 80 elements in circuit therewith and means for varying the number of effective turns in the magnet winding and also for varying the resistance of the magnet circuit to prevent "hunting action."

13. In a regulator system, a supply circuit, resistance-varying means in said supply circuit, a regulator for varying the operation of said means in accordance with supply-circuit conditions, said regulator comprising an electromagnet, and means for varying the external resistance of the magnet circuit to prevent "hunting action."

14. In a regulator system, a supply circuit, a resistance-varying means connected to said circuit and means comprising a regulator 95 for governing the operation of said means, said regulator comprising an electromagnet energized in accordance with the current flowing through the supply circuit and means comprising two resistors for varying the 100 electromagnet circuit to prevent hunting action by the regulator.

15. In a furnace-regulator system, the combination comprising a movable electrode, a motor for raising and lowering the electrode, means comprising an electromagnet for governing the operation of said motor, and means for varying the circuit of said magnet to change its setting when the electrode is being raised or lowered.

16. In a regulator system, the combination comprising a supply circuit, resistance-varying means in said supply circuit, means comprising a magnet for varying said resistance-varying means in accordance with supply-circuit conditions, an impedance device in circuit with said magnet and means for varying the value of said impedance device in the magnet circuit.

In testimony whereof, I have hereunto 120 subscribed my name this 20th day of June, 1919.

CLARENCE A. BODDIE.
